CLAIM

The ornamental design for a mobile phone, as shown and described.

DESCRIPTION

FIG. 1 is a rear perspective view of the mobile phone;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged rear view for clarity of illustration.

The dash-dot broken lines immediately adjacent to the claim represent the bounds of the claimed design while all other evenly spaced broken lines are directed to environment and are for illustrative purposes only, the broken lines form no part of the claimed design. The thicker dash-dot broken line rectangle in the FIG. 8 view is used to identify the enlarged view, is for reference purposes only, and forms no part of the claimed design.

1 Claim, 7 Drawing Sheets
